(57) **CLAIM**

The ornamental design for a removable door cover for charger, as shown and described.

DESCRIPTION

FIG. 1 is a rear, top, and left side perspective view of a removable door cover for charger.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines shown in the figures are for the purpose of illustrating portions of the removable door cover for charger that form no part of the claimed design.

1 Claim, 7 Drawing Sheets
